(57) **CLAIM**

I claim the ornamental design for the stand for displaying samples, as shown and described.

DESCRIPTION

FIG. 1 is a left-side elevational view of the stand for displaying samples, the right-side elevational view being a mirror image. The view illustrates the stand, a dome, a trash

can, a napkin-tooth pick holder, and a tag holder on which product information may be placed.

FIG. 2 is a front elevational view thereof.

FIG. 3 is a back elevational view thereof.

FIG. 4 is a top plan view thereof.

FIG. 5 is a top plan view with the trash can, napkin-tooth pick holder, and tag holder removed for the sake of clarity.

FIG. 6 is a top plan view with the trash can, napkin-tooth pick holder, tag holder, and dome removed for the sake of clarity.

FIG. 7 is an exploded perspective view of the stand for displaying samples showing how the dome, trash can, napkin-tooth pick holder, and tag holder are combined with the stand to form the completed assembly of FIGS. 1-4.

FIG. 8 is a front plan view of the tag holder shown in isolation of the stand for the sake of clarity, which tag holder is a cut and folded envelope of at least translucent plastic.

FIG. 9 is a back plan view of the tag holder shown in isolation of the stand for the sake of clarity.

FIG. 10 is a side elevational view of the tag holder shown in isolation of the stand for the sake of clarity.

FIG. 11 is a front elevational view with the napkin-tooth pick holder shown in isolation of the stand for the sake of clarity.

FIG. 12 is a back elevational view with the napkin-tooth pick holder shown in isolation of the stand for the sake of clarity.

FIG. 13 is a left side elevational view with the napkin-tooth pick holder shown in isolation of the stand for the sake of clarity, the right side elevational view being a mirror image.

FIG. 14 is a front elevational view with the trash can shown in isolation of the stand for the sake of clarity.

FIG. 15 is a back elevational view with the trash can shown in isolation of the stand for the sake of clarity; and,

FIG. 16 is a left side elevational view with the trash can shown in isolation of the stand for the sake of clarity, the right side elevational view being a mirror image.

The broken lines are for illustrative purposes only and form no part of the claimed design.
